Farnsworth Television and Radio Corporation,
a corporation of Delaware

Application December 11, 1940, Serial No. 369,623

7 Claims. (Cl. 274—10)

This invention relates to phonograph apparatus, and more particularly to automatic record-changing apparatus of improved and simplified construction.

The automatic record-changing apparatus of the present invention differs from most previous mechanisms in that the records are handled only at their edges, their center holes being utilized solely for centering the records with respect to the turntable. In such previously used automatic record-changing mechanisms, the center holes of the records were utilized not only to center the records but also to assist in the record-changing operation. The mechanism of the present invention, therefore, provides, to a new degree, safety for the records from breakage or other damage, particularly chipping around the center hole with resultant enlargement thereof.

An object of the present invention is to provide a compact record-changing apparatus of improved and simplified construction.

A further object of the invention is to provide an improved automatic record-changing mechanism which handles the records entirely at their edges and hence operates with the minimum likelihood of damaging them.

In accordance with the present invention, there is provided an automatic record-changing apparatus comprising means for supporting a stack of records above a turntable by engaging the peripheral edge portions of the lowermost supported record. A spindle extends upwardly through the center apertures of the stacked records, this spindle permitting lateral movement of the lowermost supported record. Means are provided for first moving the lowermost supported record laterally whereby it is separated from the stack. Additionally, peripheral engaging means are provided which are adapted first to support and then simultaneously to release the separated record, whereby the latter remains substantially parallel to the turntable as it drops into playing position thereon.

It is an additional feature of the invention to employ a pair of unitary members for performing the separating and releasing operations on the lowermost record. Also in accordance with the invention, a second pair of unitary members may be employed for performing these operations when the mechanism is adjusted for use with a second size of records. The phonograph apparatus also includes a tripping mechanism associated with the pickup arm for initiating the operation of the record-separating means and of the record-releasing means when the

stylus reaches the innermost groove of each of the records.

For a better understanding of the invention, together with other and further objects thereof, reference is made to the following description taken in connection with the accompanying drawings, and its scope will be pointed out in the appended claims.

In the accompanying drawings:

10 Fig. 1 is a top plan view of the apparatus in accordance with the invention, with the unplayed records removed but with a record on the turntable in playing position;

15 Fig. 2 is a right-side elevation, taken on the line 2—2 of Fig. 1 and partly in section, showing a group of records supported over the turntable and a record on the turntable in playing position;

20 Fig. 3 is a rear elevation of the apparatus of Fig. 1, showing the cam arrangement for raising and lowering the pickup arm;

Fig. 4 is a bottom plan view of the apparatus of Fig. 1;

25 Fig. 5 is a fragmentary view, taken on the line 5—5 of Fig. 4, showing the reversing mechanism for operating one of the record-supporting means;

30 Figs. 6—9 show right-side elevations, partly in section, of the unplayed records, and represent respectively successive steps in the separation and release of the lowermost record;

Fig. 10 is a perspective view, partly in section, of one of the record-supporting and releasing means; and

35 Fig. 11 is a fragmentary view, partly in section, showing the friction clutch used for initiating the record-changing cycle.

To simplify the following description, it has been assumed that the record-changing mechanism is adapted automatically to play a group of twelve-inch records, hereinafter called large records, or a group of ten-inch records, herein-after referred to as small records. The same mechanism is also adapted manually to play records of any size up to twelve inches. It will be understood, of course, that a record-changing mechanism in accordance with the present invention may readily be designed to play records of different nominal sizes from those above mentioned for purposes of illustration, without departing from the scope of the invention.

Referring now more particularly to Figs. 1 and 2 of the drawings, the invention here illustrated embodies a phonograph apparatus including a base plate 1 supporting a horizontally rotatable

turntable 2, upon which is shown a record 3 in position to be reproduced. A pickup 4 is mounted at the end of a pickup arm 5, which is pivoted at the opposite end about a vertical axis on a shaft 6 (Fig. 3). The shaft 6 is rotatable within a pedestal 7 to permit the pickup 4 to move across the face of the record as its stylus 8 tracks the groove of the record.

A stack of unplayed records 9 is supported above the turntable by diametrically opposite record supports 10A and 10B. These record supports extend upwardly from the base plate 1 to which they are fixedly secured. At the upper ends of the supports 10A and 10B swively mounted bracket members 11A and 11B are provided. In Figs. 1 and 2, the bracket members 11A and 11B are shown in the position to support small records. They may be rotated 90° counterclockwise (Fig. 1) to adapt them to support large records, or 90° clockwise from the position shown to permit unloading of the played records or manual operation of the phonograph apparatus.

As shown in Fig. 2, the turntable 2 is provided with a centering spindle 12, which extends upwardly and terminates in a tapered portion 13 extending from the top of the spindle to a point slightly below the upper surface of the uppermost record. This tapered portion facilitates loading records upon the bracket members 11A and 11B. The turntable 2 is driven by means of an electric motor 14, a pulley 15 on the motor shaft engaging a friction wheel 16 which, in turn, engages the inner surface of the flange at the edge of the turntable 2. The lower end of the spindle 12, which rotates with the turntable 2, has secured to it a pinion gear 17 (Fig. 4). The turntable 2 and the spindle 12 rotate continuously during operation of the phonograph apparatus.

When a record on the turntable has been completely played, the movement of the pickup arm toward the center of the record initiates the operation of a tripping mechanism, presently to be described, and causes a cam gear 18 to be moved far enough so that its teeth mesh with the teeth of the pinion gear 17. The cam gear 18 thereupon is driven through one complete revolution about a fixed shaft 19, and comes to rest in the position shown in Fig. 4. The cam gear 18 has several teeth removed from it at 20, the purpose of the mutilation being to break the driving connection between the pinion gear 17 and the cam gear 18. One complete revolution of the cam gear 18 defines one complete cycle of the record-changing operation as will be evident later.

The cam gear 18 is provided with a cam surface 21, as shown in Figs. 3 and 4. An arm 22, pivoted intermediate its ends on a bracket 23, which is fixed to the base plate 1, carries a roller 24 at one end which is biased by a spring 25 into engagement with the cam surface 21. As the roller 24 follows the cam surface 21, the other end of the arm 22 moves up and down. This movement moves a pin 26 (Fig. 3) vertically in the hollow shaft 6. The upper end of the pin 26 engages the under side of the pickup arm 5 in such a manner as to raise the stylus 8 from the surface of the record 3 when the roller 24 passes over the high portions of the cam surface 21.

As shown in Figs. 3 and 4, a lever 27 is affixed to the lower end of the hollow shaft 6, to the upper end of which is attached the pickup arm 5. A horizontal movement of the lever 27 effects a corresponding movement of the pickup arm 5, and vice versa. The free end of the lever

27 supports a pin 28 which moves within an aperture 29 in the heel of an L-shaped lever 30. The aperture 29 is large enough so that the pin 28 may move freely with the lever 27 over a wide arc corresponding to the movement of the pickup arm 5 while playing a record. The L-shaped lever 30 is pivoted at 31. A toe 32 of the L-shaped lever 30 engages a cam surface 33 provided on the cam gear 18. This toe 32 is maintained in contact with the cam surface 33 by a spring 34. After the stylus 8 has been raised from the surface of the record 3, in the manner previously described, and as the cam gear 18 continues to rotate, the cam surface 33 moves the L-shaped lever 30 in a counterclockwise direction (Fig. 4) about its axis 31, thereby causing the right-hand side of the aperture 29 to engage and drive before it the pin 28. The pin moves the lever 27, and therewith the pickup arm 5, in a radial direction away from the center of the record. The cam surface 33 is so shaped that the L-shaped lever 30 ceases its counterclockwise rotation when the pickup arm reaches a position beyond the edge of the turntable and the record thereon.

Referring now to Figs. 2, 4 and 10 of the drawings, the means for supporting the stack of unplayed records above the turntable and for separating the lowermost record of the stack will now be described. The bracket members 11A and 11B are mounted upon the upper end of tubular shafts 35A and 35B, respectively, (Figs. 2 and 10), which are rotatable about vertical axes within the supports 10A and 10B. Secured to the lower end of each one of the shafts 35A and 35B is a sprocket wheel 36, more clearly shown in Fig. 4. The sprocket wheels 36 engage a connecting means comprising a pair of toothed members 37 and 38, preferably in the form of levers, which are joined by a bar 39. This connecting means or lever mechanism allows the record supports to be moved in unison to any one of three positions: supporting position for large records, supporting position for small records, and non-supporting or unloading position. This is accomplished by manually moving either one of the bracket members 11A and 11B. The bracket members are locked in the desired position by the provision of a locking cam 40 secured to the lower end of the shaft 35A. The cam 40 is provided with notches 41, 42 and 43, which are engaged by a pin 44 secured to the end of a lever 45, which in turn is pivoted at 46 and held into engagement with the cam 40 by means of a spring 47.

The detailed construction of the rear record supporting and separating means is shown in Fig. 10. The bracket member 11B is provided with a first pair of slots 48 and a second pair of slots 49, the slots 48 guiding a sliding member 50B having record-supporting lips 51B, and the slots 49 guiding a sliding member 52B having record-supporting lips 53B. The sliding member 50B is provided with a slot 54 positioned transversely to its direction of sliding, and the sliding member 52B is provided with a similarly disposed slot 55. The sliding members 50B and 52B are actuated by a pin 56B, which extends through the hollow shaft 35B, and which is arranged to be moved within the shaft 35B on a pivotal bearing 57 positioned near the midpoint of the pin 56B. The upper end of the pin 56B passes through the slots 54 and 55 in the members 50B and 52B, respectively.

The lower end of the pin 56B freely engages

a hole 58 in a member 59, as shown in Fig. 4. The member 59 is pivoted at 60 to the base plate 1, and is normally maintained by a spring 61 in such a position that the lower end of the pin 56B is approximately centered in the hollow shaft 35B. The lower end of the pin 56A in the front supporting means 10A freely engages a hole 62 in a member 63, as shown in Fig. 5. The member 63 is pivoted to the base plate 1 by a pin 64, and is normally maintained by a spring 65 in such a position that the lower end of the pin 56A is approximately centered in the hollow shaft 35A. A connecting member 66 is pivoted at one end to the member 59 at 67 and, at its other end, to a member 68, by means of the pivot pin 69. The pin 69 extends downward (Fig. 5) far enough normally to engage the bifurcated end 70 of the member 63. The other end of the member 68 is slidably pivoted at 71 to the base plate 1. The member 68 has fixed to it a pin 72 arranged to engage the bifurcated end 73 of the member 63 at such times when the pin 69 is not in engagement with the bifurcated end 70 of the member 63.

The record-separating and releasing operation will now be described in connection with Figs. 4, 6-9 and 10. When the cam gear 18 revolves in a clockwise direction (Fig. 4), a long pin 73, extending from the upper surface of this gear, engages a portion 74 of the member 59 and causes the latter member to rotate in a clockwise direction about its pivot 60. This causes the lower end of the rod 56B to be moved outwardly, which in turn moves the sliding member 50B inwardly with respect to the center of the turntable. At the same time, the sliding member 50A is moved outwardly with respect to the center of the turntable. These motions of the sliding members 50A and 50B cause the lowermost record 75 to be pushed to the left until its right-hand edge drops off the bracket member 11B and falls slightly to a position where it is supported by the lips 51B. The right-hand edge of the second lowermost record now rests upon the sliding member 50B. This phase of the operation is shown in Fig. 6.

As the cam gear 18 continues to revolve, the long pin 73 clears the portion 74 of the member 59, permitting the latter to be returned to its normal position by the spring 61. Presently the long pin 73 engages the portion 76 of the member 59, causing the latter to rotate in a counterclockwise direction about its pivot 60, which in turn causes the sliding member 50B to move to its extreme outward position and, due to the linkage 66 and 63, causes the member 50A to move to its extreme inward position. The lowermost record 75 is thus pushed to the right until its left-hand edge drops off the bracket 11A. This phase of the operation is shown in Fig. 7.

As the cam gear 18 continues its rotation, the pin 73 passes out of engagement with the portion 76 of the member 59, thereby permitting the latter to be restored, by the spring 61, to its normal position. The lower ends of the pins 56A and 56B are therefore again centered in the hollow shafts 35A and 35B, and the sliding members 50A and 50B are restored to their respective mid-positions. The lowermost record 75 is thus centered over the turntable. This phase of the operation is shown in Fig. 8.

As the cam gear 18 continues its rotation, a short pin 77, mounted upon and extending upwardly from the upper surface of this gear, engages a cam member 78 attached to the member 75

59, causing the latter to rotate in a counterclockwise direction about its pivot 60. This motion of the member 59 causes the lower end of the pin 56B to move inwardly, so that the sliding member 50B moves outwardly with respect to the center of the turntable. Simultaneously, the long pin 73 engages a cam member 79 attached to the lever 66, forcing the lower end (Fig. 4) of this lever to the right against the biasing action of a spring 113, thereby causing the pin 69 to disengage itself from the bifurcated end 70 of the member 63 and causing the pin 72 to engage the bifurcated end 73 of the member 63. Following the reversing operation just described, the last-mentioned counterclockwise rotation of the member 59 results in a clockwise rotation of the member 63 about the pivot pin 64. This in turn causes the lower end of the pin 56A to move inwardly, thereby causing the sliding member 50A to move outwardly. The simultaneous outward movement of the sliding members 50A and 50B causes the lowermost record 75 to be released by the record-supporting lips 51A and 51B, after which it drops upon the turntable 2 into playing position. Immediately after the lowermost record is released, the springs 61 and 65 move the members 59 and 63 back to their normal positions, and the spring 113 moves the members 66 and 68 laterally to move pins 69 and 72 to the normal position shown in Fig. 5. This record-releasing phase of the cycle is shown in Fig. 9.

As will be observed from Figs. 6-9, the spindle 12 is so notched at 80, and the rotation of the spindle 12 is so timed with respect to the lateral movement of the sliding members 50A and 50B, as to permit the lowermost record 75 to be moved laterally in the manner just described without interference from the spindle 12. It is pointed out that the separating and releasing of the lowermost record is accomplished entirely without relying upon the spindle for support of or movement of this record. It is also emphasized that, while the upper end of the spindle 12 is notched as described above and as shown in the drawings, the continuous rotation of the spindle will insure that the center apertures of the stacked records will remain aligned properly to position the records upon the supporting brackets 11A and 11B.

The automatic record-changing cycle effected by a complete revolution of the cam gear 18 is initiated by the automatic tripping mechanism, previously mentioned, which will now be described in greater detail. In moving toward the center of the record during the playing thereof, the pickup arm 5 moves with it the hollow shaft 6 which has secured to it a clutch 81 (Figs. 3 and 11). This clutch comprises a flanged sleeve 82 affixed to the hollow shaft 6, and a plate 83 to which are affixed the lever 84 and an ear 85 and which is mounted in frictional relationship with the flanged portion of the sleeve 82. A suitable fiber washer 86 is placed over the plate 83. A plate 87 with a turned-down ear 88 is placed over the fiber washer 86. A spring washer 89 is placed over the plate 87. A flanged cover member 90 is screwed on the sleeve member 82 far enough so that the bottom of the flanged portion of cover 90 rests upon the spring washer 89. The spring washer 89 maintains an even frictional engagement between the plate 83 and the fiber washer 86 when the members 82 and 90 are screwed together. A spring 91 is connected to

the outer flange of the member 82 and to the turned-down ear 88 of the plate 87.

Referring particularly to Fig. 4, a lever 92 is pivotally supported at one end for rotation about the shaft 6. Thus, as reproduction goes on and the pickup arm moves toward the center of the record, the clutch 81 moves the lever 84 in a counterclockwise direction (Fig. 4). The lever 84 engages the side of the lever 92, as more clearly shown in Fig. 3, moving it in a counterclockwise direction. The free end of the lever 92 preferably is turned downwardly at a right angle and engages the lower end (Fig. 4) of a lever 93 which is pivotally mounted intermediate its ends to base plate 1. The upper end of the lever 93 engages the upper end of a starting member, preferably in the form of a lever 94, which is pivotally mounted intermediate its ends, by means of the pin 95, to the upper surface of the cam gear 18.

Each time the cam gear 18 makes a complete revolution, the upper end of the lever 94 engages the upper end of lever 93, which is so shaped that its engagement with the lever 94 causes the upper end of the latter to move toward the surface of the cam gear 18 and the lower end to move out of the path of a pin 95, attached to and rotating with the spindle 12. The lower end of the lever 94 rests against a boss 96 attached to and extending upwardly from the cam gear 18. The purpose of this boss is to stiffen the lever 94 against movement in a horizontal plane. As the pickup arm 5 approaches the inner groove of a record, it moves the levers 84, 92 and 93 in a counterclockwise direction (Fig. 4). The lower end of the lever 93 carries a leaf spring 97 which lies in the path of a cam 98 attached to the spindle shaft 12. The cam 98 periodically strikes the spring 97 and moves the lever 93, and with it the levers 92 and 84, in a clockwise direction (Fig. 4), the lever 84 changing its position with respect to the pickup arm by virtue of the clutch 81. When the stylus 8 moves into the eccentric or coarse-pitched spiral groove customarily provided as the innermost groove of the record, the lever 84 can be moved by the cam 98 in a clockwise direction only against the biasing action of the spring 91. When this occurs, the cam 98 temporarily may move the levers 93, 92 and 84 clockwise, but these levers immediately thereafter are returned in a counterclockwise direction by the action of the spring 91 on the lever 84. The return movement is so great that the lever 93 is moved out of engagement with the lever 94. The latter lever thereupon moves in a vertical plane to position its catch portion 99 in the path of the pin 95. As the pin 95 is rotated, it engages the catch portion 99 and moves it, and the lever 94 in a horizontal plane, whereby the cam gear 18 is rotated far enough so that its teeth mesh with the teeth of the pinion gear 17, after which the pinion gear continues to drive the cam gear 18 through a complete revolution to effect the cycle of automatic record changing.

As appears in Fig. 4, a fixed stop 100 is secured to the base plate 1 with an upturned end 101 positioned in the path of movement of the lever 84. As the pickup arm is swung beyond the edge of the turntable and the records thereon during a record-changing cycle, it moves the lever 84 in a clockwise direction (Fig. 4) into engagement with the stop 100. This engagement is effected, however, before the pickup arm has swung to its outermost position. The lever 84, therefore, is caused to change its angular position with respect

to the pickup arm, this change being permitted by the slipping connection of clutch 81. This operation positions the lever 84 well forward of the pickup arm as the latter returns toward the center of the record, and insures positive engagement of the elements 84, 92 and 93 before the stylus 8 reaches the innermost groove of the record.

As previously noted, the record-supporting brackets 11A and 11B are shown in the drawings in the proper position for playing small records automatically. When it is desired to play large records automatically, the supporting brackets 11A and 11B are rotated 90° in a counterclockwise direction (Fig. 1). In this case, the separation and release of the lowermost record is performed by the sliding members 52 (Fig. 10) instead of by the sliding members 50. Otherwise, the operation is similar.

When changing record sizes, it is also necessary to alter the amount by which the pickup arm is swung inwardly to its initial playing position. Referring to Fig. 4, this adjustment is accomplished automatically by means of a cam 102 secured to the lower end of the hollow shaft 35B. A lever 103, pivoted to the base plate 1 intermediate its ends, carries a pin 104 which is maintained in contact with the cam 102 by means of a spring 105. The other end of the lever 103 carries a set screw 106 which, when the record-supporting brackets 11A and 11B are positioned to support large records, is adapted to engage an upturned ear 107 of a lever 108 secured to the L-shaped lever 30. With the record-supporting brackets 11A and 11B positioned as shown in Fig. 4 for the playing of small records, the set screw 106 does not make contact with the ear 107, and the toe portion 32 of the lever 30 is permitted to follow the cam surface 33 during the complete revolution of the cam gear 18. When the record-supporting brackets 11A and 11B are turned to the position for supporting large records, however, the pin 104 drops into the hollow 109 of the cam 102, and the set screw 106, in cooperation with the ear 107 and the lever 108, prevents the lever 30 from moving as far in a clockwise direction (Fig. 4) as it otherwise would, whereby the pickup arm is swung less inwardly than is the case when the apparatus is arranged for playing small records. Thus it is evident that the manual positioning of the brackets 11A and 11B for supporting a stack of either small or large records automatically sets the mechanism for so positioning the pickup arm that the stylus engages the initial groove of the record about to be played.

In addition to the automatic trip mechanism previously described, there is also provided manual means for initiating the record-changing cycle, as for example when it is desired to reject a record. This means comprises a spring-biased trip lever 109 pivotally mounted at 110 on the base plate 1, as shown in Fig. 4. The lower end of this lever is bent to extend upwardly through an aperture in the base plate 1, a suitable knob 111 being attached to the upwardly bent end, as shown in Fig. 1. The lever 109 is normally biased by a spring 112 out of engagement with the turned-over end of the lever 93, but it may be manually moved to engage lever 93 and hence to initiate a record-changing cycle by moving lever 93 in a counterclockwise direction far enough to disengage its upper end from the upper end of lever 94.

The general mode of operation of the record-

changing apparatus will now be described. After a stack of records has been placed upon the brackets 11A and 11B (Fig. 2) and a record 3 has been placed in playing position upon the turntable 2, the pickup arm 5 is moved manually to place the stylus 8 in the starting groove of the record on the turntable.

The pickup arm 5 moves inwardly as the stylus tracks the spiral groove of the record and eventually reaches the innermost groove, at which time the automatic tripping mechanism is operated by the movement of the levers 84, 92 and 93 (Fig. 4) in response to the movement of the pickup arm 5, whereby the levers 93 and 94 disengage, and the catch portion 99 moves in a vertical plane into the path of the pin 95 provided on the spindle shaft 12.

Engagement of the pin 95 with the catch portion 99 on the lever 94 causes the cam gear 18 to be rotated until the teeth of this gear mesh with the teeth of the pinion gear 17, after which the cam gear 18 is driven by the pinion gear 17 through one revolution to complete a record-changing cycle.

As the cam gear rotates, the cam surface 21 (Figs. 3 and 4) moves the lever 22 and raises the pickup arm 5 off the record. Continued movement of the cam gear 18 causes the cam surface 33 (Fig. 4) to move the L-shaped lever 30 and therewith the lever 27 to swing the pickup arm beyond the edge of the record on the turntable.

Shortly thereafter, the pin 73 (Figs. 4 and 10), on the cam gear 18, engages the portion 74 of the member 59 and moves the latter to cause a corresponding movement of the sliding members 50A and 50B (or 52A and 52B, depending upon the setting of the brackets 11A and 11B). This movement of the sliding members 50A and 50B moves the lowermost record 75 (Fig. 6) laterally far enough so that it drops off the bracket 11B onto the lips 51B. The continued rotation of the cam gear 18 causes the pin 73 to disengage itself from the portion 74 of the member 59, and to engage the portion 76 thereof. The resultant movement of the member 59 causes the sliding members 50A and 50B to move the lowermost record 75 laterally in the opposite direction so that its edge drops off the bracket 11A onto the lips 51A (Fig. 7). As the pin 73 disengages itself from the portion 76 of the member 59, the latter returns to its normal position, causing the sliding members 50A and 50B to center the lowermost record 75 with respect to the spindle 12 (Fig. 8).

As the cam gear 18 continues its rotation, the short pin 71 engages the cam member 78 attached to the member 59, and simultaneously the pin 73 engages the member 79 attached to the lever 66. These two engagements produce such displacements of the members 59, 66, 68 and 63 that the lowermost record 75 is released by a simultaneous outward movement of the sliding members 50A and 50B, and gently drops into playing position on top of the record 3 (Fig. 9).

The cam gear 18 has, by this time, rotated far enough so that the cam surface 33 (Fig. 4) allows the L-shaped lever 30 to move clockwise, under the biasing action of the spring 34, to return the pickup arm 5 to a position where the stylus 8 is over the starting groove of the new record.

At this time, the cam surface 21 (Fig. 3) has rotated to the point where the lever 22 permits the stylus 8 to descend into engagement with the record. Immediately thereafter, the cam gear 18

comes to rest in the position shown in Fig. 4 of the drawings, and reproduction of the record just placed on the turntable takes place.

The next and following cycles of automatic operation are initiated by the automatic trip mechanism each time the stylus moves into the innermost groove of the record. The last record of the stack will be repeated automatically until the mechanism is manually turned off.

Unloading of the played records is accomplished by first rotating the brackets 11A and 11B to the unloading position, where they are out of the way when the stack of records is lifted vertically off the turntable. If these brackets are left in this position, a single record may be played manually, the automatic mechanism functioning merely to repeat this record until the mechanism is turned off. It will be apparent to those skilled in the art that means may readily be provided whereby the automatic mechanism which causes a manually played record to be repeated may be disengaged when the brackets 11A and 11B are rotated to the loading position. Such a feature may be added to the mechanism of the present invention without departing from the scope thereof, and has been omitted from the drawings and description merely to avoid unnecessary complication thereof.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An automatic record-changing apparatus comprising a turntable; a pair of oppositely disposed supports relative to said turntable for supporting a stack of records above said turntable by engaging peripheral edge portions of the lowermost supported record; a spindle extending upwardly from said turntable and through the centering apertures of a stack of supported records, said spindle having a recessed portion for permitting lateral movement of the lowermost supported record relative to said spindle; a pair of members slidably mounted on said supports for being moved toward and away from said spindle, said members having record-engaging portions above the surfaces of said supports for moving the lowermost supported record therefrom and record-supporting extensions below said supports; means for moving said members in a first direction for moving the lowermost supported record off of one of said supports and onto the record-supporting extension supported thereby; means for moving said members in a second direction for moving the lowermost supported record off of the other of said supports and onto the record-supporting extension supported thereby; means for simultaneously moving said members away from said spindle for releasing said lowermost supported record from said record-supporting extensions for permitting it to fall into centered position on said turntable.
2. An automatic record-changing apparatus comprising a turntable; a pair of oppositely disposed supports relative to said turntable for supporting a stack of records above said turntable by engaging peripheral edge portions of the lowermost supported record; a spindle extending upwardly from said turntable and through the cen-

tering apertures of a stack of supported records, said spindle having a recessed portion for permitting lateral movement of the lowermost supported record relative to said spindle; a pair of members slidably mounted on said supports for being moved toward and away from said spindle, said members having record-engaging portions on the surfaces of said supports for moving the lowermost supported record therefrom and record-supporting extensions below said supports; means for moving in a first direction one of said pair of members for moving the lowermost supported record off of one of said supports and onto the record-supporting extension supported thereby; means for moving in a second direction the other of said pair of members for moving the lowermost supported record off of the other of said supports and onto the record-supporting extension supported thereby; means for simultaneously moving said pair of members away from said spindle for releasing said lowermost supported record from said record-supporting extensions for permitting it to fall into centered position on said turntable.

3. An automatic record-changing apparatus comprising a turntable; a pair of oppositely disposed supports relative to said turntable for supporting a stack of records above said turntable by engaging peripheral edge portions of the lowermost supported record; a spindle rotatably connected with said turntable and extending upwardly therefrom through the centering apertures of a stack of supported records, said spindle having a recessed portion for permitting lateral and downward movement of the lowermost supported record relative to said spindle; a pair of members slidably mounted on said supports for being moved toward and away from said spindle, said members having record-engaging portions on the surfaces of said supports for moving the lowermost supported record therefrom, record-centering portions below said supports and record-supporting extensions below said supports; means for moving said members in a first direction for moving the lowermost supported record off of one of said supports and onto the record-supporting extension supported thereby; means for moving said members in a second direction for moving the lowermost supported records off of the other of said supports and onto the record-supporting extension supported thereby; means for restoring said members to their normal position whereby said record-centering portions center said lowermost supported record relative to said spindle; and means for simultaneously moving said members away from said spindle for releasing said lowermost supported record from said record-supporting extensions for permitting it to fall into centered position on said turntable.

4. An automatic record-changing apparatus comprising a turntable; a pair of oppositely disposed supports relative to said turntable for supporting a stack of records above said turntable by engaging peripheral edge portions of the lowermost supported record; a spindle extending upwardly from said turntable and through the centering apertures of a stack of supported records, said spindle having a recessed portion for permitting lateral and downward movement of the lowermost supported record relative to said spindle; a pair of members slidably mounted on said supports for moving toward and away from said spindle, said members having record-engaging portions on the surfaces of said supports for

5 moving the lowermost supported record therefrom and record-supporting extensions below said supports; means for operatively connecting said members whereby they may be moved together; means for moving said members in a first direction for moving the lowermost supported record off of one of said supports and onto the record-supporting extension supported thereby; means for moving said members in a second direction for moving the lowermost supported record off of the other of said supports and onto the record-supporting extension supported thereby; means for simultaneously moving said members away from said spindle for releasing said lowermost supported record from said record-supporting extensions for permitting it to fall into centered position on said turntable.

10 5. An automatic record-changing apparatus comprising a turntable; a spindle extending upwardly from said turntable and through the centering apertures of a stack of supported records, said spindle having a recessed portion for permitting lateral movement of the lowermost supported record relative to said spindle; a pair of movable members positioned above said turntable and diametrically opposite relative thereto, said members being movable to a first position for supporting a stack of records of relatively large diameter and being movable to a second position for supporting a stack of records of relatively small diameter; a first supporting edge on each of said members for engaging a peripheral edge portion of the lowermost supported record of a stack of records of relatively large diameter when said members are in said first position and a second supporting edge on each of said members for engaging a peripheral edge portion of the lowermost supported record of a stack of records of relatively small diameter when said members are in said second position; first elements mounted on said members for moving over said first edges toward and away from said spindle when said members are in said first position and second elements mounted on 20 said members for moving over said second edges toward and away from said spindle when said members are in said second position; first elements and said second elements having record-engaging portions above the record-supporting surfaces of said edges and record-supporting extensions below the record-supporting surfaces of said edges; means for moving said first elements in a first direction when said members are in said first position and for moving said second elements in said first direction when said members are in said second position whereby when a lowermost supported record is on said first edges it is moved off of one of said first edges and onto said record-supporting extension therebelow 25 and when a lowermost supported record is on said second edges it is moved off of one of said second edges and onto said record-supporting extension therebelow; means for moving said first elements in a second direction when said members are in said first position and for moving said second elements in said second direction when said members are in said second position whereby the lowermost supported record is moved off of the other of said supporting edges 30 and onto said record-supporting extension therebelow; and means for simultaneously moving away from said spindle said first elements when said members are in said first position and said second elements when said members are in said second position whereby the record supported by 35 40 45 50 55 60 65 70 75

said extensions is released for falling into centered position on said turntable.

6. An automatic record-changing apparatus comprising a rotatable turntable; a spindle extending upwardly from said turntable and through the centering apertures of a stack of supported records, said spindle having a recessed portion for permitting lateral movement of the lowermost supported record relative to said spindle; a pair of movable members positioned above said turntable and diametrically opposite relative thereto, and being operatively associated with each other for being moved in unison to a first position for supporting a stack of records of relatively large diameter and being moved in unison to a second position for supporting a stack of records of relatively small diameter; a first supporting edge on each of said members for engaging a peripheral edge portion of the lowermost supported record of a stack of records of relatively large diameter when said members are in said first position and a second supporting edge on each of said members for engaging a peripheral edge portion of the lowermost supported record of a stack of records of relatively small diameter when said members are in said second position; first elements mounted on said members for moving over said first edges toward and away from said spindle when said members are in said first position and second elements mounted on said members for moving over said second edges toward and away from said spindle when said members are in said second position, said first elements and said second elements having record-engaging portions above the record-supporting surfaces of said edges and record-supporting extensions below the record-supporting surfaces of said edges; means for moving said first elements in a first direction when said members are in said first position and for moving said second elements in said first direction when said members are in said second position whereby when a lowermost supported record is on said first edges it is moved off of one of said first edges and onto said record-supporting extension therebelow and when a lowermost supported record is on said second edges it is moved off of one of said second edges and onto said record-supporting extension therebelow; means for moving said first elements in a second direction when said members are in said first position and for moving said second elements in said second direction when said members are in said second position whereby the lowermost supported record is moved off of the other of said supporting edges and onto said record-supporting extension therebelow; and means for simultaneously moving away from said spindle said first elements when said members are in said first position and said second elements when said members are in said second position whereby the record supported by said extensions is released for falling into centered position on said turntable.

7. An automatic record-changing apparatus comprising a rotatable turntable; a spindle ex-

tending upwardly from said turntable and through the centering apertures of a stack of supported records, said spindle having a recessed portion for permitting lateral movement of the lowermost supported record relative to said spindle; a pair of movable members positioned above said turntable and diametrically opposite relative thereto and being operatively associated with each other for being moved in unison to a first position for supporting a stack of records of relatively large diameter and being moved in unison to a second position for supporting a stack of records of relatively small diameter; a resilient means associated with one of said members for maintaining said members rigidly in either said first or second positions at different times; a first supporting edge on each of said members for engaging a peripheral edge portion of the lowermost supported record of a stack of records of relatively large diameter when said members are in said first position and a second supporting edge on each of said members for engaging a peripheral edge portion of the lowermost supported record of a stack of records of relatively small diameter when said members are in said second position; first elements mounted on said members for moving over said first edges toward and away from said spindle when said members are in said first position and second elements mounted on said members for moving over said second edges toward and away from said spindle when said members are in said second position, said first elements and said second elements having record-engaging portions above the record-supporting surfaces of said edges and record-supporting extensions below the record-supporting surfaces of said edges; means for moving said first elements in a first direction when said members are in said first position and for moving said second elements in said first direction when said members are in said second position whereby when a lowermost supported record is on said first edges it is moved off of one of said first edges and onto said record-supporting extension therebelow and when a lowermost supported record is on said second edges it is moved off of one of said second edges and onto said record-supporting extension therebelow; means for moving said first elements in a second direction when said members are in said first position and for moving said second elements in said second direction when said members are in said second position whereby the lowermost supported record is moved off of the other of said supporting edges and onto said record-supporting extension therebelow; and means for simultaneously moving away from said spindle said first elements when said members are in said first position and said second elements when said members are in said second position whereby the record supported by said extensions is released for falling into centered position on said turntable.

HARVEY C. HABEGGER.
